C. L. BESLER.
WATER REGULATOR FOR ENGINE RADIATORS.
APPLICATION FILED APR. 12, 1916.

Patented June 27, 1916.

UNITED STATES PATENT OFFICE.

CHARLES L. BESLER, OF WINFIELD, KANSAS.

WATER-REGULATOR FOR ENGINE-RADIATORS.

1,188,882.

Specification of Letters Patent. Patented June 27, 1916.

Application filed April 12, 1916. Serial No. 90,717.

To all whom it may concern:

Be it known that I, CHARLES L. BESLER, a citizen of the United States, residing at Winfield, in the county of Cowley and State of Kansas, have invented certain new and useful Improvements in Water-Regulators for Engine-Radiators; and I do hereby declare the following to be a full, clear, and exact description of the invention, such as will 10 enable others skilled in the art to which it appertains to make and use the same.

This invention relates to the water-cooling of internal combustion engines, especially those of automobiles; and the object of the 15 invention is to provide for the maintenance of a uniform water-level in the radiator at all times.

The invention has been devised for use more particularly in connection with water 20 regulating apparatus, for which Letters Patent No. 1,170,475 were granted to me on the first day of February, 1916, to which reference may be had for specific details in connection with a brief and general description 25 following.

In the accompanying drawing, Figure 1 is a sectional view illustrating the invention as applied to an automobile. Fig. 2 is a longitudinal section of the main water regulating device as shown in the above mentioned 30 patent. Fig. 3 is a similar view of the auxiliary or overflow regulator which forms the subject matter of this application.

In the above mentioned patent the apparatus 35 for maintaining a uniform water-level in the radiator 1 is a surplus water supply tank 2, preferably mounted under the cowl 3, at a somewhat higher level than the top of the radiator, and feeding said radiator by 40 gravity through the medium of a water-regulator shown in Fig. 2. This comprises a small chamber 4, connecting with the supply-tank by a pipe 5, and with the radiator by an outlet pipe 6. The flow of water through the 45 outlet is controlled by a float 7 and a water cut-off consisting of a flexible tube 8 connecting with the outlet and a pinching blade 9 coöperating with the float and the base of the float support to close said tube.

In the practical use of the device above 50 described a difficulty was encountered, arising out of the expansion and boiling of the water in the radiator when the engine was very hot. This would cause the radiator to 55 overflow at the overflow pipe, and thus con-

tinually draw water from the surplus tank, eventually draining it. This difficulty is overcome by the present invention, the overflow being returned to the surplus tank, and the only waste in the water being due to 60 slow evaporation, and practically negligible.

Referring now to the drawings, 10 denotes a small chamber conveniently located with respect to the top of the radiator. Herein it is shown taking the place of the usual filling 65 nozzle, the body of the chamber being set down within the upper part of the radiator. The upper portion of the chamber or vessel may serve as a filling nozzle 11, and is provided with a tightly closing cap 12. The 70 bottom of this nozzle (the neck of the vessel) forms a valve-seat 13 for a valve 14 carried on suitable stems 15 connecting at their lower ends with a float 16. When the water in the radiator and chamber are at the normal level 75 the valve is closed, as shown. When by evaporation the water sinks below the normal level the float sinks, opening the valve. This opens an air-vent 17, normally closed by the valve, and thus permits water from 80 the surplus tank to enter the radiator by the action of its regulating mechanism already described, it being understood that the radiator is otherwise hermetically sealed, the 85 usual overflow pipe being dispensed with.

In the top of the valve 14 is seated a small valve 18, whose stem 19 runs in a guide 20 forming part of a bridge 21 across the nozzle. The small valve is held down on the larger one by a light spring 22. From 90 the neck of the vessel a pipe 23 runs back to the supply tank. It will thus be evident that when there is an excess of water or pressure in the radiator the surplus water or steam will be forced through the small valve and 95 back into the supply tank, to be there condensed and so restored to the cooling system.

Owing to the agitation of the water near the surface in the radiator, when boiling, the 100 chamber containing the float 16 should preferably not be open to the water near the top, but should be fed by a pipe 24 leading to near the bottom of the radiator. The main supply is shown as connected with this pipe, 105 but the connection of the supply with the radiator may be separate, if desired. The vent at 25 is for the escape of water condensing in the neck of the vessel, and to prevent freezing therein in cold weather. 110

Having thus described my invention, I claim:

1. Combined with the radiator of a combustion engine, provided with an air-vent, a closure for said vent actuated by the water-level in the radiator, and means adapted to automatically supply water to said radiator.
2. Combined with a vented radiator for a combustion engine, a closure for said vent actuated by the rising and falling of water in the radiator, an auxiliary water supply, means adapted to automatically deliver water therefrom to the radiator as needed, and means coöperating with the vent-closer to restore to said water supply the surplus water in the radiator due to boiling or expansion.
3. Combined with a radiator and means adapted to automatically supply it with water at a normal level, a valve normally closed by light pressure, a chamber therefor, and a pipe leading from said chamber to said water supply, whereby the overflow due to expansion or boiling in the radiator is restored to the cooling system.
4. Combined with a radiator and means adapted to automatically supply it with water at a normal level, a float-valve adapt-
- ed to close the radiator hermetically, an auxiliary, light pressure valve, a chamber therefor, and a pipe leading from said chamber to the water supply.
5. Combined with a radiator and means adapted to automatically supply it with water at a normal level, a float-valve adapted to close the radiator hermetically, a chamber therefor, a water connection of said chamber with still water near the bottom of the radiator, an auxiliary valve opened by light pressure from inside the radiator, a chamber for said valve, and a communication of said chamber with the main water supply.
6. Combined with a radiator and means adapted to automatically supply it with water at a normal level, a float chamber holding water at the water-level in the radiator, a float therein, a valve closed thereby to tightly close the radiator, an auxiliary valve coöperating with the float valve, and opened by light pressure from within the radiator, a chamber therefor having air and drain-vents closed by the float-valve, and a pipe leading from the auxiliary valve chamber to the main water supply.

In testimony whereof I affix my signature.
CHARLES L. BESLER.
